UNITED STATES PATENT OFFICE.

GEORGE ROSS, OF KANSAS CITY, MISSOURI.

PROCESS OF PRODUCING ROAD-SURFACING MATERIAL.

1,252,722.

Specification of Letters Patent.

Patented Jan. 8, 1918.

No Drawing.

Application filed July 21, 1917. Serial No. 183,621.

To all whom it may concern:

Be it known that I, GEORGE Ross, a citizen of the United States, residing at Kansas City, in the county of Jackson and State of Missouri, have invented certain new and useful Improvements in Processes of Producing Road-Surfacing Material, of which the following is a specification.

This invention relates to a process of producing a road surfacing material, and has for its object the production of a cheap surfacing material which is practically water proof, is not affected by extreme temperature, and is extremely durable under the impact and grinding action of traffic.

With this general object in view the invention consists in the novel process of producing the surfacing material as hereinafter described and claimed.

20 In the production of the material, earthy material is combined with water, asphalt or other bitumen and a solvent for dissolving the asphalt or the like and crushed rock, gravel or sand.

25 In carrying out the process, the earthy material which may be collected from or near the road to be surfaced, is broken up or comminuted in any suitable manner and mixed with a sufficient quantity of water to 30 make a thin mud, the mixing being done in an excavation or hole in the ground or in a tank.

Hot liquefied bitumen or the like is then thoroughly mixed with the mud, pulverized bitumen being used in preference to the liquefied bitumen if the bitumen is to be transported any great distance by slow traffic, as when the pulverized bitumen is used no heating for the same is required.

40 A solvent, such as dead oil, creosol, crude carbolic acid or other asphalt solvent, is added in sufficient quantities to dissolve the bitumen.

The bitumen being thoroughly dissolved 45 by the solvent, then becomes thoroughly incorporated with the earthy material.

The mixing may be performed in any suitable manner by means of machinery or by manual power like mortar.

50 The earthy material may be loam, soil or clay, but a highly colloidal deflocculated clay is preferable if the best possible surfacing material is desired.

The following proportions of the ingredients gives most satisfactory results, but I do 55 not desire to restrict myself to such propor-

tions as differences in the earthy material or in the bitumen may make it advisable to change the relative proportion of the ingredients.

60 Earthy material 100 parts. Water by weight 35% of the total weight of the earthy material. Bitumen by weight 20% of the total weight of the earthy material. Solvent 5% by weight of the weight of the bitumen.

65 The function of the solvent is to obtain a perfect saturation of the bitumen or asphalt in the earthy material without the use of heat, it being obvious that a great economy is effected where it is possible to effect a 70 thorough saturation of the bitumen or the like in earthy material, without heating the mixture, or any of the ingredients thereof, as the heating operation involves the use of expensive machinery, fuel and labor.

75 In this process the solvent is held in the mud by surface tension while the bitumen is held in suspension in very fine particles until the evaporation of the water occurs. At this point the solvent dissolves the bitumen and the saturation of the latter in the earthy material begins and continues until the solvent has evaporated, leaving a very perfectly bituminated or bituminized material, which being thoroughly and uniformly 80 saturated with the bitumen, is tough, plastic, malleable and water proof, the mixture of earthy material and bitumen giving this result. The crushed rock, gravel or sand im- 85 parts rigidly to the wearing surface.

90 During the process of making road surfacing material with a hot liquefied bitumen, the contact of the latter with the cold mud after the solvent has been added causes the former to foam and during the mixing 95 process the thin films of bitumen produced by the foaming action thereof are broken up into very fine particles and hence result in a most uniform distribution of the bitumen in the earthy material.

100 The material may be deposited upon the road immediately or without deterioration, may be kept for many months in tanks or cisterns from which evaporation of moisture cannot take place.

105 From the foregoing it will be apparent that I have evolved a process of producing a very durable road surfacing material, at low cost, and it will be obvious that due to the fact that the material can be quickly repaired and laid by hand, a road can be maintained in perfect condition at a minimum ex-

pense, and it will be understood that while this surfacing material is designed chiefly for country roads, it may be used for surfacing city streets with splendid results. If desired the mixture of bitumen with mud, may be spread on the road to be surfaced and the solvent sprayed or sprinkled on the material after substantially all of the water has evaporated therefrom. In dry warm **10** weather the solvent will penetrate the entire mass in a few hours and within a day or so the road can be opened to traffic.

I claim:

15 1. The method of producing a surfacing material for roads and the like, consisting in mixing earthy material with water to produce a thin mud, then adding bitumen and a solvent for the latter, the entire mass being agitated to effect uniform distribution of the bitumen in the mud.

20 2. The method of producing a surfacing material for roads and the like, consisting in mixing earthy material with water to produce a thin mud, then adding bitumen

and a solvent for the latter, the entire mass **25** being agitated to effect uniform distribution of the bitumen in the mud, and mixing the thin mass with crushed rock, gravel or sand.

3. The method of producing a surfacing material for roads and the like, consisting in **30** mixing earthy material with water to produce a thin mud, then adding bitumen and a solvent for the latter, the entire mass being agitated to effect uniform distribution of the bitumen in the mud, mixing the thin **35** mass with crushed rock, gravel or sand, and then compacting the mixture on a roadway.

4. The method of producing a surfacing material for roads and the like, consisting in **40** mixing earthy material with water to produce a thin mud, then adding bitumen to the mud and mixing it therewith, then spreading the mixture on the road and finally depositing a solvent for bitumen, on the surfacing material after the same has become **45** substantially dry.

In testimony whereof I affix my signature.
GEORGE ROSS.
